UNITED STATES PATENT OFFICE.

WILLIAM ESTY, OF LACONIA, NEW HAMPSHIRE, ASSIGNOR TO ESTY SPRINKLER COMPANY, OF LACONIA, NEW HAMPSHIRE, A CORPORATION OF NEW HAMPSHIRE.

AUTOMATIC STATIONARY FIRE-EXTINGUISHER.

1,211,834.

Specification of Letters Patent.

Patented Jan. 9, 1917.

Application filed September 27, 1911. Serial No. 651,483.

To all whom it may concern:

Be it known that I, WILLIAM ESTY, of Laconia, in the county of Belknap and State of New Hampshire, have invented certain 5 new and useful Improvements in Automatic Stationary Fire-Extinguishers, of which the following is a specification.

The present invention consists in improvements in that class of automatic fire 10 extinguishers which are employed in factories and other buildings for the purpose of automatically flooding the same with water in case of the outbreak of a fire, and relates to the sprinkler head.

15 The objects of the present improvements are in the main similar to those of United States Letters Patent No. 931,190, dated August 17, 1909, namely, to provide a resilient frame for the sprinkler head for the 20 purpose of putting the valve under tension to resist normal pressures within the pipe system and to permit the opening of the valve should an excessive temperature be reached; and to furnish a fusible collapsible 25 strut interposed between the valve and the resilient frame which cannot get displaced and is prompt and efficient in action in case of a fire.

The improvements are illustrated in the 30 accompanying drawings, wherein—

Figure 1, is a front view of a sprinkler head embodying the improvements. Fig. 2, is a vertical section. Figs. 3, 4, 5 and 6 are detail perspective views of the several parts 35 of which the strut is composed. Fig. 7, is a view of the several parts of the sprinkler head, exclusive of the strut, which are shown separated from each other and arranged in linear order. Fig. 8, is a view 40 looking in the direction of the arrow 8, in Fig. 7, and showing the upper end of the coupling nut and the part of the sprinkler frame which engages said nut. Fig. 9, is an under side view of the valve.

45 The improved sprinkler is composed of a distributer A; a resilient frame B; a separable valve C; a coupling nut D; and a separable strut E, interposed between the valve and the resisting abutment a, carried 50 by the frame B. The separable strut is composed of three distinct parts, namely, a

multiplying lever F, a valve lever G, and a frame lever H. When the sprinkler is ready for installation, as shown in Figs. 1 and 2, these three strut members are united 55 together by readily fusible solder located along the several joints between the strut members, as indicated by the hatching at b, in Fig. 1. A packing is employed between the under face of the valve C, and the valve 60 seat c (Fig. 7), of the coupling nut D, which is composed of a round disk of mica I, between two round disks K, of waxed fiber, which are preferably employed but which are omitted from Figs. 1, and 2, because the 65 additional lines would confuse the illustration. Hence, in Figs. 1, and 2, the mica disk I, is alone shown.

In the aforesaid Letters Patent No. 931,190, the sprinkler head frame furnished 70 the seat for the valve and it was provided with an integral coupling boss, and it was necessary to put the sprinkler head under compression for the purpose of putting the strut in place. In accordance with the 75 present invention the sprinkler frame B, does not carry the valve seat, but said seat is on the separate coupling nut D. This coupling nut is formed with two threaded sections d, and e, and an intermediate polygonal zone f, for the reception of a wrench. 80 By means of the lower threaded section e, the sprinkler head may be attached to a fitting of a pipe system. The upper threaded section d, of the coupling nut screws into an 85 interiorly threaded collar L, which is an integral part of the resilient frame B. The integral frame B, comprises the threaded collar L, side arms M, merging into each other at the top of the frame, lateral outwardly projecting yielding side loops O, 90 uniting the respective side arms with the collar L, the strut abutment a, and a hollow boss g, at the extreme upper end, over which is slipped the distributer A, shown in Fig. 2, 95

the upper end of the boss being upset upon the distributer to hold it in place, as in said Patent No. 931,190. The resilient lateral outwardly projecting side loops O, increase the resilience of the frame and, by appropriate distribution of the metal, the frame 100 can be constructed so as to exert any pres-

sure which may be desired for a particular installation. These lateral outwardly projecting side loops O, extend beyond the upwardly extending sides of the frame and 5 each loop comprises two separated laterally extending arms connected together by the bowed outer portions. The laterally projecting side members of each bowed loop can yield to and from each other, depending 10 upon the strains imparted to the strut. The laterally projecting yielding side loops O extend outwardly beyond the outer face of the corresponding side arms to such an extent that the eye of each loop extends likewise beyond the outer face of the corresponding side arm. The lower leg of each loop which joins with the collar, extends in a direction substantially at right angles to the line of strain between the collar and 15 abutment and the upper leg of each loop, which joins with the side arm, extends approximately in a direction at right angles to the line of strain. The result of this construction is that the sprinkler frame is adequately strong and at the same time is sufficiently yielding. By reason of the laterally projecting yielding side loops O extending out beyond the main portions of the side arms M of the frame, inwardly extending or 20 reentrant bends P, are formed, and these bends in connection with the outwardly projecting loops O give the desired yielding character to the frame. The valve C, has depending lugs h (as in said Patent No. 35 931,190) which fit around the periphery of the valve seat, as shown in Fig. 1, thereby preventing the lateral displacement of the valve and of the mica and fiber packing I, K. The valve is furnished at the middle of 40 its upper face with a central boss i, having a rounded crown upon which the strut may pivot.

The valve lever G, of the strut has a bottom flange j, and a plate k. The flange j, on 45 its under side (see Fig. 6) has a hemispherical socket l, at its middle which is adapted to fit the crown of the valve boss i, and to constitute therewith a pivotal step bearing for the strut. On its upper face the flange 50 j, has two recesses m, near its ends to receive projecting feet o, at the bottom of the multiplying lever F. The frame lever H, has a plate p, and a flange q, at an angle thereto and this flange at the middle of its upper 55 face has an ellipsoidal or elongated recess r, which is adapted to fit the rounded elongated crown of the abutment a. The strut is assembled by laying the faces of the two plates k and p, of the levers G, and H, together, so that the flange q, of the lever H, 60 will rest and fulcrum upon the upper angular edge s, of the lever G, as shown in Fig. 2. The multiplying lever lies against the outer face of the plate p, of the lever H, and its

feet o, fit into the recesses m, in the flange 65 of the lever G, and constitute a pivotal connection between said levers. The three members are then united by a low-test solder. Each of the three strut members has a central through hole t, and when the three members are assembled these holes register with each other to constitute a single through passage, as shown in Fig. 2. The purpose of these registering holes is to facilitate the transmission of heat to the soldered surfaces 75 of the strut.

The sprinkler is assembled by partly screwing the coupling nut D, to the collar L, of the frame, putting the valve, packings, and strut into position, and by then screwing 80 the coupling nut home in the collar until the upper face or limiting shoulder of the polygonal zone f, seats against the bottom face of the collar L, as shown in Fig. 2. This screwing up of the coupling nut, acting 85 through the valve, forces the strut against the abutment a, of the frame and expands the frame B, through the spreading apart of the yielding loops O, thereby putting the desired permanent tension upon the strut. 90

In the event of a fire, the solder of the strut is melted and, owing to the tension of the resilient frame on the strut, the members of the strut are ruptured and torn apart with certainty and instantaneously. The 95 construction of the strut insures the flying apart of its members so soon as the solder is weakened by heat and before the valve is lifted far enough to permit the escape of water, which otherwise might chill the solder 100 and prevent the full opening of the valve. As soon as the solder is sufficiently softened, the tension on the strut causes the two levers G, and H, to swing apart on the fulcrum formed by the flange q, resting on the edge s, 105 of the plate k, so that the lower edge of the plate p, of lever H, swings outwardly to a relatively large extent and, as this lower edge of plate p, is close to the fulcrum between the multiplying lever F, and the 110 flange j, said multiplying lever is thrown outwardly at once, thus removing its soldered surfaces entirely out of reach of the other members of the strut.

Owing to the elongated or ellipsoidal 115 shape of the recess r, fitting the correspondingly shaped crown of the abutment a, the strut is maintained permanently in the position shown in Figs. 1, and 2, with the sides of the strut within and protected by the side 120 arms M, of the frame, so that the strut is protected from accidental blows. Also, what is of greater importance, the strut is thus maintained in its position for certain operation, since it can fly open to its full extent in case of a fire without encountering the frame, which encounter would occur if the strut stood at right angles to the posi- 125

tion shown in Figs. 1, and 2. By reason of the elongated bearing between the abutment and the upper end of the strut, and the pivotal step bearing between the lower end of the strut and the valve, the strut turns with the frame when the frame is screwed down to its proper adjustment to expand the frame at the side loops and to put tension upon the strut.

- 10 It is the commercial practice in the manufacture of sprinkler heads to assemble them with the parts in correct position and under proper tension at the place of manufacture and it is important that the proper 15 adjustment, being once reached, should not be altered either accidentally or intentionally. Accordingly, it is important that, after the parts have been properly assembled, the coupling nut should be locked 20 against unscrewing from the sprinkler frame. Accordingly, the collar L, of the sprinkler frame is provided with notches w, at its upper face and extending from its 25 interiorly threaded center. When the coupling nut has been screwed home, the threads of the section d, of the nut, where they are exposed at the notches w, are pressed into the notches by any appropriate tool, thereby locking the nut from turning. In Fig. 2, 30 these nut-locking notches are shown at the most exposed portions of the collar L, but it is preferable that they should be located in line with the spring loops O, as shown in Fig. 8, so as to avoid any weakening of the 35 frame by reason of their presence.

All of the parts of the sprinkler (excepting the packing I, K) are made of metal of the character customarily employed. All of the parts can be made of a non-corrodible 40 composition of copper and tin, but phosphor-bronze, manganese bronze, or any other non-corrodible metal capable of being cast may be employed. Preferably, however, the multiplying lever F, is made of German 45 silver. In Figs. 10, and 11, are shown modified forms of the multiplying lever. The lever F¹, shown in Fig. 10, is a wire bent to form two legs x, x, which rest against the outer face of the strut lever H, and are soldered thereto. The lower ends of the legs x, x, fit in suitable spaced recesses m¹, m¹, in the flange j, of the valve lever G¹, shown in Fig. 12. The multiplying lever F², shown in Fig. 11, has its base uppermost, and its two 50 feet o¹, o¹, at its narrow end fit in the recesses m¹, m¹, of the valve levers shown in Fig. 12. This lever F², is soldered against the outer face of the lever H, just as in the case of the lever F. In installing such sprinkler heads, 55 they are usually placed above the pipes to which they are connected so that they stand as shown in the drawings. They may, however, be used in any position; but the phrasology herein describing direction and posi-

tion is based on the assumption that the 65 sprinkler head is upright as shown in the drawings.

I claim:

1. A collapsible strut for a sprinkler comprising, in combination, a valve lever with 70 an angular upper edge and a flange at its bottom having a valve registering recess at the middle of its underside and two spaced recesses on its upper face; a frame lever having a flange at its top resting on the angular upper edge of said valve lever, said flange having an abutment registering recess at the middle of its upper face, said frame lever lying face to face against said valve lever; and a multiplying lever lying against 75 the outer face of said frame lever and having projecting feet at its bottom entering said spaced recesses in the upper face of the flange of said valve lever, and said three levers being united together by fusible 80 solder.

2. A sprinkler head having an integral frame comprising a threaded collar, side arms, a strut abutment at the juncture of the side arms and opposite the center of said collar, and laterally projecting resilient side loops, each of which connects the collar with one of the side arms, the eye of each loop extending outwardly beyond the outer face of the corresponding side arm, and both 90 legs of the loop extending in a direction substantially at right angles to the line of strain between the collar and abutment, in combination with a nut screwing into said collar, said nut having a limiting shoulder 95 seating against said collar and a valve seat; means for positively locking said nut and collar together after the collar is seated on said shoulder; a valve fitting on said valve seat; and a collapsible fusible strut between 100 said valve and abutment.

3. A sprinkler head having an integral frame comprising a threaded collar, side arms, a strut abutment at the juncture of the side arms and opposite the center of said 110 collar; and laterally projecting resilient side loops, each of which connects the collar with one of the side arms, the eye of each loop extending outwardly beyond the outer face of the corresponding side arm, and the leg 115 of the loop which joins the collar extending in a direction substantially at right angles to the line of strain between the collar and abutment, in combination with a nut screwing into said collar, said nut having a limiting shoulder seating against said collar and a valve seat; means for positively locking said nut and collar together after the collar is seated on said shoulder; a valve fitting on 120 said valve seat; and a collapsible fusible strut between said valve and abutment.

4. A sprinkler head having a resilient frame, a threaded collar, and a strut abut-

ment, in combination with a nut screwing into said collar, said nut having a limiting shoulder seating against said collar and a valve seat; means for positively locking said nut and collar together after the collar is seated on said shoulder; a valve fitting on said valve seat; and a collapsible fusible strut between said valve and abutment.

In witness whereof, I have hereunto signed my name in the presence of two sub- 10 scribing witnesses.

WILLIAM ESTY.
